UNITED STATES PATENT OFFICE.

LOUIS BURGESS, OF NEW YORK, N. Y., ASSIGNOR TO STANDARD OIL COMPANY, A CORPORATION OF NEW JERSEY.

PROCESS FOR THE PRODUCTION OF ANHYDROUS ALUMINUM CHLORIDE.

1,405,183.

Specification of Letters Patent. Patented Jan. 31, 1922.

Application filed May 13, 1919. Serial No. 296,792.

To all whom it may concern:

Be it known that I, LOUIS BURGESS, a citizen of the United States, residing at New York city, in the county of New York and State of New York, have invented certain new and useful Improvements in Processes for the Production of Anhydrous Aluminum Chloride, of which the following is a specification.

10 My invention relates to new and useful improvements in processes for the production of anhydrous aluminum chloride.

According to my present invention, finely divided aluminum carbide is suspended in 15 hydrochloric acid gas, and an exothermic reaction is initiated by the application of heat, in order to produce anhydrous aluminum chloride. The process is preferably performed by forming a mixture of aluminum carbide and hydrochloric acid gas by suspending the former in the latter, and 20 flowing said mixture into a reaction chamber, wherein an application of heat causes a reaction between the carbide and the acid 25 gas, thereby producing the aluminum chloride.

I have fully and clearly illustrated in the accompanying drawings one apparatus adapted to carry out in a preferred manner 30 the process of my invention.

In said drawings, Figure 1 is a vertical central section through said apparatus; and

Fig. 2 is an enlarged view of a portion of the apparatus shown at the left of Fig. 1.

35 I will first describe the apparatus, and in connection with the operation thereof to be set forth later, will describe my new and improved process.

1 designates a hopper or container adapted 40 to contain ground or pulverized aluminum carbide which is to be acted upon by dry hydrochloric acid gas, to produce anhydrous aluminum chloride. The outlet end of this hopper 1 is connected to a trough 2, the latter being closed at one end by an end-wall 3, and provided at its opposite end with an outlet preferably in the form of a cylindrical spout 4 opening into the receiving end of a chute 5, the outlet end 6 of which is connected 45 to the upper wall 7 of a reaction chamber or furnace 8 into which the chute 5 is adapted to deliver material contained in the hopper 1. Arranged in the bottom of the trough 2 and extending through the spout 4, is a screw-conveyor 9 having at one end a shaft

10 journaled in a bearing 11 carried by the said end-wall 3, while at its opposite end said conveyor is mounted on a shaft 12 journaled in a bearing 13 mounted on the chute 5. The operation of the screw-conveyor is to feed 60 the loose material from the hopper 1 lengthwise of the trough 2 and spout 4 into the chute 5, and to provide for a continuous feed of such material to the heating chamber. The screw-conveyor may be driven by any 65 suitable means, preferably by an electric motor 14 suspended by a suitable hanger 15 from the bottom of the trough 2. The armature shaft of the motor carries a pinion 16, meshing with a gear 17 mounted on a 70 shaft 18 having suitable bearing in said hanger 15, and also carrying a pinion 19 meshing with a gear 20 fixed to said shaft 10. Mounted on the shaft 12 and located within the inlet end of the chute 5, are agitator plates or vanes 21 which, when the said shaft is rotated, serve to agitate, mix and 75 suspend the materials fed to said chute by the screw-conveyor.

Surrounding a portion of the trough 2 and the spout 4, is a jacket 22, said jacket providing an annular chamber 23 which is closed at one end, as at 24, and having its other end opening through an annular orifice 25 surrounding the outlet end of the spout 4. The 80 said annular chamber 23 afforded by the wall of the spout and the jacket 22, is adapted to receive hydrochloric acid gas through a supply connection 24^a, which gas flows through said orifice 25, and is mixed with the pulverized material as the latter passes to the reaction chamber, to be hereinafter described. The agitator plates 21 serve to thoroughly mix the hydrochloric acid gas and said material before they are admitted to said reaction chamber 8.

Within the reaction chamber 8 is arranged a pair of arc electrodes 26, one of which may be connected to a threaded rod 27 extending through a stuffing-box 28 on the upper wall 7, and engaged by a hand-wheel nut 29, in order that the distance between the said arc electrodes may be adjusted. The chamber is provided with a fire-brick lining 30 of any suitable type. Said chamber may also be 100 provided with a thermocouple 31 of a pyrometer adapted to be connected to a suitable measuring instrument (not shown), in order to determine the temperature within the said furnace. At its upper end, the reaction 105 furnace 8 has a flue 32 leading to a chimney 33.

chamber or furnace is connected by a duct 32, with the upper end of a condenser 33, provided with a baffle-plate 34 and a drop door 35, the latter permitting removal from the condenser of the material condensed therein. The baffle plate is preferably supported free from the sidewall and bottom of the condenser, but in such position as to intercept the volatile aluminum chloride flowing from the furnace 8. Said condenser may be also provided with a man-hole 36 and cover 37. The condenser 33 is connected at its upper portion by an outlet duct 38 with the upper portion of a second condenser 15 constructed the same as the condenser 33 just described. The latter condenser 33^a may be connected by a duct 39 with another condenser, or with a series of condensers, or said duct 39 may serve as an outlet for gases 20 if no further condensers are employed.

When employing an apparatus such as above described, the process embodying my invention is performed as follows:—

Aluminum carbide, preferably in a finely divided or pulverized condition, i. e., about 200 mesh, is placed in the hopper 1, and hydrochloric acid gas is admitted to the chamber 23 through the coupling 24^a, the said gas being supplied at such pressure as 25 will cause ready flow of the same to the furnace 8. The screw-conveyor being set into motion, the finely divided aluminum carbide is fed through the spout 4, past the orifice 25, through which the hydrochloric acid gas emerges and is mixed with the aluminum carbide. The revolving plates or vanes 21 serve to agitate the pulverized aluminum carbide and suspend it in the current of hydrochloric acid gas. Previous to 30 the feeding of the mixture of aluminum carbide and hydrochloric acid gas to the furnace chamber, the arc in the latter is established, and said chamber is heated to such a temperature as will cause aluminum carbide and hydrochloric acid gas to react exothermically to produce anhydrous aluminum chloride. The feed of the mixture of hydrochloric acid gas and aluminum carbide to the chamber may take place continuously 35 and need not be stopped, except when it is necessary to remove residues from the said furnace chamber. The reaction is continuous, and it is not necessary that the arc be maintained after the reaction is initiated, because being an exothermic reaction it will generate sufficient heat to continue the reaction. The volatile anhydrous aluminum chloride produced in the reaction chamber 40 passes through the duct 32 to the first condenser 33, where a portion of the aluminum chloride is condensed and deposited in the bottom of the condenser, from which point it may be removed through the drop door 35. The uncondensed volatile aluminum chloride and the gases generated by the re-

action pass on through the duct 38 to the condenser 33^a where further condensation takes place with deposition of the anhydrous aluminum chloride in powdered form. It will be noted that I may employ one or more condensers without departing from my invention. The baffles 34 serve to separate the inlet ducts of the condensers from the outlet ducts thereof, and provide for a circuitous path of the volatile aluminum chloride, in order to insure efficient condensation thereof. Any one or all of the condensers may be provided with a suitable outlet for the gases generated by the reaction.

It will be understood from the above description, that in performing the process according to my invention, the hydrochloric acid gas will preferably be flowed in a stream into the reaction chamber, and will be under such pressure as to have sufficient velocity to carry the suspended aluminum carbide with it. The aluminum carbide being in a very finely or pulverized condition is beaten up or agitated so as to be thoroughly suspended in the hydrochloric acid gas, and be carried by the latter into the reaction chamber in such form as to be subjected to the reaction with the hydrochloric acid gas before said carbide can drop to the bottom of the chamber. In other words, the reaction takes place between the aluminum carbide and the hydrochloric acid gas while the former is suspended in the latter, and the finely divided particles are in intimate contact with the acid gas.

What I claim and desire to secure by Letters Patent of the United States is:—

1. The process of producing anhydrous aluminum chloride, which consists in suspending finely divided aluminum carbide in hydrochloric acid gas, initiating a reaction by the application of heat thereto, and continuing the reaction exothermically.

2. The process of producing anhydrous aluminum chloride, which consists in suspending by agitation finely divided aluminum carbide in hydrochloric acid gas, initiating a reaction by the application of heat, and continuing the reaction exothermically.

3. The process of producing anhydrous aluminum chloride, which consists in continuously feeding finely divided aluminum carbide into a current of hydrochloric acid gas, mixing the said gas and aluminum carbide by agitation, passing the mixture into a reaction chamber, and initiating a reaction in said chamber by the application of heat.

4. The process of producing anhydrous aluminum chloride, which consists in continuously feeding finely divided aluminum carbide into a current of hydrochloric acid gas, mixing the said gas and aluminum carbide, by agitation, passing the mixture into a reaction chamber, initiating a reaction in said

chamber by the application of heat, and continuing the reaction exothermically.

5. The process of producing anhydrous aluminum chloride, which consists in suspending finely divided aluminum carbide in hydrochloric acid gas, initiating a reaction by the application of heat thereto, discontinuing the application of heat and then adding new material and continuing the reaction exothermically.

10 6. In the process of producing aluminum chloride, the step which consists in subject-

ing aluminum carbide in finely divided condition to the action of hydrochloric acid, the process being carried out with the materials 15 heated exothermically.

In testimony whereof I have hereunto signed my name in the presence of two subscribing witnesses.

LOUIS BURGESS.
